US00D980819S

(12) **United States Design Patent** (10) Patent No.: **US D980,819 S**
Bellham et al. (45) Date of Patent: ** *Mar. 14, 2023

(54) **HEADPHONES**

- (71) Applicant: **GN AUDIO A/S**, Ballerup (DK)
- (72) Inventors: **Philip Bellham**, Ballerup (DK);
Rasmus Trudslev Pedersen, Ballerup (DK);
Bill Zeng, Ballerup (DK)
- (73) Assignee: **GN AUDIO A/S**, Ballerup (DK)
- (*) Notice: This patent is subject to a terminal disclaimer.
- (**) Term: **15 Years**
- (21) Appl. No.: **29/829,464**
- (22) Filed: **Mar. 4, 2022**

Related U.S. Application Data

- (63) Continuation of application No. 29/738,537, filed on Jun. 18, 2020, now Pat. No. Des. 956,013.

(74) Attorney, Agent, or Firm — Hamre, Schumann,
Mueller & Larson, P.C.**CLAIM**

The ornamental design for a headphones, as shown and described.

DESCRIPTION

FIG. 1 is a top perspective view of the headphones.

FIG. 2 is a front view thereof.

FIG. 3 is a back view thereof.

FIG. 4 is a left view thereof.

FIG. 5 is a right view thereof.

FIG. 6 is a top view thereof; and,

FIG. 7 is a bottom view thereof.

The features shown in broken lines depict environmental subject matter only and form no part of the claimed design.
